(57) **CLAIM**

The ornamental design for a door cover for washing machine, as shown and described.

DESCRIPTION

FIG. 1 is a perspective view of a door cover for washing machine, showing our new design;
 FIG. 2 is a front view thereof;
 FIG. 3 is a rear view thereof;
 FIG. 4 is a side view thereof;
 FIG. 5 is another side view thereof;
 FIG. 6 is a top view thereof;
 FIG. 7 is a bottom view thereof;
 FIG. 8 is an cross-sectional view taken along line 8-8 thereof in FIG. 2;
 FIG. 9 is a cross-sectional view taken along line 9-9 thereof in FIG. 2; and,

FIG. 10 is another perspective view thereof in a washing machine environment.
 The broken lines illustrating portions of a washing machine are environmental purposes only and form no part of the claimed design.
